UNITED STATES PATENT OFFICE.

WORTHY LEE, OF BLUEHILL, NEBRASKA.

GRAIN-SCOURER.

SPECIFICATION forming part of Letters Patent No. 696,577, dated April 1, 1902.

Application filed September 11, 1901. Serial No. 75,030. (No model.)

To all whom it may concern:

Be it known that I, WORTHY LEE, a citizen of the United States, residing at Bluehill, in the county of Webster and State of Nebraska, have invented new and useful Improvements 5 in Grain-Scourers, of which the following is a specification.

This invention relates to a grain-scouring machine of that type in which pairs of coöperating rotary and stationary rubbing devices or disks are arranged in a perforated cylinder and act successively on the grain for removing the impurities and polishing the grain.

The object of my invention is to produce a 15 machine of this general character, but having rubbing devices of a novel construction, especially adapting the machine for detaching and removing without injury to the grain the outermost layer or portion of the bran, which 20 is known as "bee's wing." This outer portion of the bran is very thin and brittle and becomes finely pulverized in reducing the grain, producing fine particles or specks which it is very difficult to separate from the flour.

25 In the accompanying drawings, Figure 1 is a longitudinal sectional elevation of a grain-scouring machine embodying my invention. Fig. 2 is a cross-section in line 2 2, Fig. 1, looking forward. Fig. 3 is a cross-section in line 3 3, Fig. 1, looking rearward. Fig. 4 is a cross-section in line 2 2, Fig. 1, looking rearward. Fig. 5 is a cross-section in line 5 5, Fig. 1, looking rearward. Fig. 6 is a horizontal sectional elevation showing a slightly-modified construction of the machine.

35 Like letters of reference refer to like parts in the several figures.

A represents the perforated scouring case or cylinder, which is arranged horizontally 40 and provided at its front end with a feed-spout *a* and at its rear end with a discharge-spout *b*.

C represents the stationary rubbing partitions or disks, and D the coacting rotary rubbing and propelling devices, of which there 45 is one arranged in front of each stationary partition or disk.

E represents the horizontal shaft which carries the rotary scouring and propelling 50 devices and which is journaled in bearings *ff'* on the main frame F and is driven by a pulley *f*² or other suitable means.

A suitable number of pairs of stationary and rotary scouring devices is arranged in the cylinder, one pair behind the other, as 55 the character of the work or the nature of the grain may require. The stationary partitions or disks have concave faces *c*, which are turned toward the head of the cylinder, and the rotary devices D have corresponding 60 convex faces, which are turned rearwardly toward the concave faces of the stationary partitions. Each of the latter is provided with a comparatively small central discharge-opening *c'*, through which the shaft E passes 65 and which is somewhat larger than the shaft. The front stationary partition or disk is located near the feed end of the cylinder, and the last is preferably so arranged that its central opening discharges directly into the 70 discharge-spout *b*.

Each rotary scouring and propelling device is composed of an annular series of radial wings or blades *g*, which are secured obliquely to a hub *g'*, mounted on the shaft E. Each 75 wing has a convex rear edge *g*² of about the same curvature as the concave face of the scouring bowl or partition and projects with its rear portion into the concave face. The face or front side *g*³ of each wing, which side 80 faces the direction in which the wing rotates, is preferably concave, and the front edge *g*⁴ of each wing is preferably straight.

H indicates intermediate propellers or conveyers, one of which is secured on the shaft 85 E between each stationary bowl or disk C and the next rotary scouring and propelling device D. These propellers have radial inclined wings, such as shown, and move the grain from the rear of each stationary disk toward 90 the next rotary scouring device, so as to be acted upon by the latter.

The wings or blades *g* of the rotary scouring and propelling device are separated from each other, so that flow passages or spaces are 95 formed between the wings, which passages or spaces extend from the front to the rear edges of the wings. The grain is forced by the action of the wings through these passages or spaces and is crowded into the scouring-bowl 100 and swept around in the latter until the grain is finally forced through the central outlet of the bowl. These outlets are so small compared with the diameter of the bowl that a

considerable pressure is created upon the grain in forcing the latter toward and through each outlet, such pressure causing an effective attrition action of the kernels against each other. When the grain requires a more severe rubbing action in order to completely remove the outer layer of the bran, the convex face of the stationary disk or partition is milled or roughened, as indicated in Fig. 6; but this is not ordinarily necessary.

In the operation of the machine the cylinder is kept filled with grain, as the discharge of the grain from the several partitions takes place by reason of the pressure which is exerted upon the accumulated grain. The rotary wings sweep the grain around and at the same time exert a powerful pressure upon the grain, by which the latter is forced against the stationary partitions and through the central discharge-openings thereof. This pressure causes an attrition action between the kernels and also a rolling action as the grain is swept around, whereby the outermost layer of the bran is worked off. As the result of the treatment the kernels are not only freed from impurities, but also deprived of the thin outermost layer of the bran, usually called "bee's wing." This outermost layer is very thin and brittle and in reducing the grain produces fine specks, which lower the grade of the flour and are very difficult to separate from the flour or flour-producing parts of the grain by the usual treatment.

In operating upon certain kinds of grain the intermediate propellers or conveyers II can be omitted and the stationary bowls or partitions arranged more closely together, so that the grain passes directly from one partition to the rotary propelling and scouring device D of the next partition. This construction of the machine is shown in Fig. 6.

The fine detached material escapes through the perforations of the scouring-case and is collected or disposed of in any suitable and well-known manner. The fine detached material which escapes with the grain into the tail-spout b is separated from the grain in any suitable manner—for instance, by an air-

separator, such as is shown in the drawings, and which consists of a wind-trunk J, into which the material is discharged from the tail-spout and which leads to the eye of a fan-case K. This wind-trunk is provided with the usual chess-hopper or trap j for intercepting the heavier grade of material which is carried off by the air current.

I claim as my invention—

1. The combination of a horizontal scouring-case, a stationary partition arranged therein and having a concave face and a central discharge-opening, and a rotary scouring and propelling device which projects into the concave face of the partition and which is composed of an annular series of radial, inclined wings which face with their rear edges the concave face of the partition and which are separated by flow-passages extending between the wings from the front edges to the rear edges thereof, substantially as set forth.

2. The combination of a scouring-case, of a stationary partition arranged therein and having a central discharge-opening and a concave face, a rotary scouring and propelling device projecting into the concave face of said partition and provided with an annular series of radial inclined wings having the edges facing the partition of substantially the same curvature as the concave face of the same, substantially as set forth.

3. The combination with a scouring-case, of successive pairs of stationary partitions and coacting rotary scouring and propelling devices, said stationary partitions having concave faces and central discharge-openings, and said rotary scouring and propelling devices having inclined wings, and a propeller arranged between each partition and the next-following rotary scouring and propelling device, substantially as set forth.

Witness my hand this 19th day of August, 1901.

WORTHY LEE.
